UNITED STATES PATENT OFFICE.

WILLIAM W. BARTON, OF SALT LAKE CITY, UTAH.

HAND-TOOL.

SPECIFICATION forming part of Letters Patent No. 763,352, dated June 28, 1904.

Application filed March 25, 1903. Serial No. 149,495. (No model.)

To all whom it may concern:

Be it known that I, WILLIAM W. BARTON, a citizen of the United States, and a resident of Salt Lake City, in the county of Salt Lake 5 and State of Utah, have invented a new and Improved Hand-Tool, of which the following is a full, clear, and exact description.

This invention relates to a hand-operated device especially useful in unscrewing or 10 otherwise removing the caps or covers of jars, cans, and like receptacles and also useful as a wrench for various other purposes.

The device comprises, briefly stated, two jaw-like members having handles at one end 15 and a chain or other means for adjustably connecting together their opposite ends. Connected with the chain is a spike, which is employed in connection with the jaws for prying off covers or for various other purposes, as 20 will suggest themselves during the practical use of the device.

This specification is an exact description of one example of my invention, while the claim defines the actual scope thereof.

25 Reference is to be had to the accompanying drawings, forming a part of this specification, in which similar characters of reference indicate corresponding parts in all the views.

Figure 1 is a perspective view of the invention. Fig. 2 is a plan view showing the invention in use, and Fig. 3 is a sectional view showing the invention in use.

30 *a* indicates the two jaws of the device, which are in the form of bars, as shown, and have handles *a'* at one end. One of said jaws *a* has at the other end a hook *a²*, and these ends of the jaws are connected by a chain *b*, the links of which are enlarged or opened, so that any one of said links may be engaged 35 with the hook *a²*, thus to vary the length of the connection between the jaws *a*. Connected with the chain *b* intermediate its length is a second chain *c* or equivalent connection, and from this chain *c* is hung a spike or prying-tool *d*, preferably formed with a slightly-bent and pointed end *d'*.

The inner faces of the jaws *a* are formed with two groups of serrations, designated *a³* and *a⁴*, respectively, the group *a³* being the 40 larger and being formed on a curve, so that they may be effectively engaged with a circu-

lar cover in the manner illustrated in Fig. 2. The other group of teeth, *a⁴*, is relatively small and curved on a shorter radius, so as to adapt these parts of the jaws *a* to grip smaller articles, such as a pipe or nut. On the upper sides of the jaws *a* ledges *a⁵* are formed or fastened thereto, and said ledges are each intended to serve as fulcrum on which to rock the spike *d*. 55

In using the invention the chain *b* should be adjusted until the jaws *a* properly engage the article which is to be operated upon, and then by grasping the handles *a'* the jaws may be operated as desired. If the vessel-closure is 60 not a threaded one, it may be first loosened by the application of the jaws *a*, and then by gripping the receptacle below the closure and placing the spike *d* on one of the ledges *a⁵* the point of the spike may be engaged with 65 the inclosure, and by using the spike as a lever said cover may be lifted from its seat. Various other operations may be performed with the tool, as will be apparent, and this adapts it to general household and domestic 70 uses. 75

Various changes in the form, proportion, and minor details of the invention may be resorted to at will without departing from the spirit and scope thereof. Hence I consider 80 myself entitled to all such variations as may lie within the intent of my claim.

Having thus described my invention, I claim as new and desire to secure by Letters Patent—

A tool, comprising two jaws having handle 85 portions at one end and each having a raised portion or ledge intermediate its ends, a chain having its ends respectively connected with the ends of the jaws opposite the handle portions thereof, one of the jaws having a hook 90 thereon with which the intermediate links of the chain are capable of intermediate connection, for the purpose specified, and a spike or prying-tool connected to the chain intermediate the ends thereof. 95

In testimony whereof I have signed my name to this specification in the presence of two subscribing witnesses.

WILLIAM W. BARTON.
